CLAIM

The ornamental design for a stand for portable electronic device as shown and described.

DESCRIPTION

FIG. 1 is a front perspective view of a stand for portable electronic device showing our new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left elevational view thereof.

FIG. 7 is a right elevational view thereof; and,

FIG. 8 is a rear perspective view thereof.

The broken lines in the drawing figures depict portions of the stand for portable electronic device that form no part of the claimed design. The interior surfaces defined by the rectangular

(Continued)

gular opening visible on the bottom and left side of the article form no part of the claimed design.
